PROCESS FOR TREATING HYDROCARBON
OIL

Harold R. Snow, Neodesha, Kans., assignor to
Standard Oil Company (Indiana), Chicago, Ill.,
a corporation of Indiana

Application May 3, 1933, Serial No. 669,081

12 Claims. (Cl. 196—47)

This invention relates to improvements in processes for the thermal conversion of heavy hydrocarbon oil into lighter products and relates more specifically to processes according to which the oil to be converted is subjected to a plurality of successive heating and vaporizing steps.

In accordance with my invention fresh charging stock, such as crude oil, is stripped successively by vapors derived from a tar flashing operation, vapors from a viscosity breaking cracking operation and vapors from a vapor phase cracking operation, the fully stripped charging stock then being subjected to the viscosity breaking operation already mentioned. A final desired distillate such as gasoline, as well as a heavier clean condensate is formed from the lighter vapors of the vapor phase cracking operation combined with the lighter vapors from the stripped crude and this condensate is used as the charging stock for the vapor phase cracking operation. Other condensate products are also segregated as a result of the crude stripping operation, a particular advantage being that the tarry residues produced by the vapor phase cracking operation and the viscosity breaking operation are separately collected for individual disposal.

My invention will be explained more fully in the following description taken in conjunction with the accompanying drawing.

30 The drawing shows diagrammatically a system for treating hydrocarbon oil in accordance with my invention.

In the drawing reference numeral 1 indicates a crude oil flash tower; 2 an evaporator tower; 3 a fractionator tower; 4 a fuel oil flash tower; 5 a viscosity breaking heater or furnace; 6 a vapor phase heater or furnace; and 7 a vapor phase soaking drum. Fresh charging stock, such for example as 36° A. P. I. Mid-Continent crude, is forced by action of pump 17 through charging line 8 and heat exchanger coils 9 and 10 located in the tops of the fractionator tower and flash tower respectively, into the primary or light naphtha flash drum 11 of crude flash tower 1. In this tower, because of the rise in temperature secured by passage through the heat exchanger coils, light naphtha vapors are separated from the rest of the crude charge. These vapors are removed from the top of the drum through vapor line 12 and condenser 13 for storage in receiver 14, after being subjected to a certain amount of fractionation as a result of passage through the bubble trays or other fractionating devices 15, which are supplied with any necessary cooling

ing stock is a topped crude or other oil low in naphtha content the flash drum 11 may be eliminated and the preheated charge may be introduced directly into secondary flash drum 18.

The unvaporized portion of the fresh charging stock is removed from the bottom of flash drum 11 and introduced into an intermediate point in a secondary flash drum 18 through pipe 19. The oil enters the drum 18 at an intermediate point in a series of baffle plates 20, and is therein partially vaporized by the aid of heat derived from hot products introduced through line 21 into the lower portion of the flash drum 18. The resulting vapors rise in the drum, being subjected to partial condensation by the action of the bubble 15 trays or other fractionating devices 22 and any necessary cooling fluid introduced through the conduit 23. The light vapors remaining uncondensed pass off from the drum 18 through vapor line 24 and condenser 25, the resulting condensate being collected in receiver 26. The flash drum 18 is also provided with trap out trays 27 and 28, as well as with additional baffle plates 29 located below the latter trap out tray. Light gas oil collects on trap out tray 27 and is withdrawn through conduit 30 for storage in receiver 31, or for any further treatment desired. A heavier condensate and unvaporized residue of the crude charge is collected on trap out tray 28, removed through pipe line 32, and forced by 30 action of pump 33 into an intermediate point in the evaporator tower 2, above a series of baffle plates 34.

The evaporator tower has also bubble trays or other fractionating devices 35, located above the 35 baffle plates first mentioned, as well as a trap out tray 36. Below this trap out tray is arranged a series of baffle plates 37 and a conduit 38 is provided for introducing a suitable cooling agent on top of these baffle plates. The reduced crude and 40 condensate oil introduced into the evaporator 2 through line 32 flow downwardly over baffle plates 34 and meet a rising current of vapors produced by the introduction of hot cracked products into the base of the evaporator through conduit 39, 45 with the result that the rising vapors are cooled and partially condensed, while the introduced oil is heated. Unvaporized portions of the introduced oil and condensed portions of the rising vapors are caught on trap out tray 36, removed 50 through pipe line 40 and introduced into tank 41, preferably insulated, which serves as a source of supply for the viscosity breaking heater 5. The preheated stock contained in the tank 41 is withdrawn through pipe line 42 and introduced, 55

by action of the pump 43, into the viscosity breaking heater 5, from which it emerges at a moderate cracking temperature, e. g. 860° F., and passes through the line 21, already mentioned, 5 into the lower part of flash drum 18, as described hereinbefore.

The vaporous products remaining uncondensed by passage upwardly through the evaporator pass off from the top thereof through vapor line 44 10 into the lower part of fractionator tower 3. A cooling coil 45 is positioned in the top of the evaporator tower to control the character of the emerging vapors, fresh charging stock or any other desired cooling medium being passed 15 through the coil in the well known manner. In the fractionator tower 3 the introduced vapors undergo fractionation to separate vapors of products in the gasoline boiling point range, the resulting condensate, being clean and suitable for 20 vapor phase cracking, is withdrawn from the base of the fractionator tower through pipe line 53 and introduced by action of pump 46 into the vapor phase heater 6, from which the products emerge at a relatively high cracking temperature, 25 for example 925 to 935° F., and are preferably transferred through conduit 47 into the soaking drum 7, but if desired the vapors may be bypassed around the drum 7 through pipe 41, by proper manipulation of valves 48' and 49'. In 30 this drum further cracking and digestion of the products take place, the temperature being substantially the same as that of the products leaving the vapor phase heater. The digested products then travel through conduit 39 into the lower 35 part of the evaporator tower as already mentioned. The gasoline vapors remaining uncondensed by the fractionating action of tower 3 emerge from the top thereof and pass through vapor line 48 and condenser 49, the condensate 40 formed being collected in receiver 50, from which any necessary portion of the distillate can be returned through pipe 51, by action of pump 52, into the top of the fractionator tower, as a refluxing medium. The coil 9, through which the 45 relatively cool fresh charging stock passes, also aids in the fractionating operation in the well known manner.

Tar is withdrawn from the bottom of evaporator 2 through drawoff line 54 having reducing 50 valve 55 therein and preferably is introduced into the flash tower 4, which is maintained under a lower pressure, such as atmospheric pressure for example. In the flash tower the tar separates into vapors which move upwardly through fractionating devices 56, such as baffle plates, partial condensation occurring, and the vapors remaining uncondensed pass off from the top of the tower through vapor line 57 into the secondary flash drum 18, below the baffle plates 20. Coil 10 55 in the top of the flash tower provides the necessary cooling for effecting the partial condensation mentioned. Unvaporized portions of the tar, which may be suitably between 5 and 20° A. P. I. gravity, are withdrawn from the base of the flash 60 tower 4 through drawoff line 58 and sent to storage. The flashing operation may be dispensed with and the tar may be withdrawn from the system through line 54' if desired. Unvaporized crude residue, which may be between 4 and 12° 65 A. P. I. gravity is withdrawn from the bottom of secondary flash drum 18 through draw-off line 59 and passed to storage. This residuum is especially suitable for manufacturing certain types of asphalts and paving materials and it may also

be employed for flushing the vapor line 1a as will be described hereinafter. Also, it may be blended with cracked tar and other oils to meet Bunker C fuel oil specifications. This residue may be steam stripped prior to withdrawal, if desired, steam inlet pipe 59' being provided for this purpose. 5

The conditions in flash tower 1 are subject to variation depending on the particular charging stock used. For the charging stock specifically mentioned hereinbefore, i. e. 36° A. P. I. Mid-Continent crude, the temperature of the preheated stock entering flash drum 11 might be, for example, about 450° F., while the temperature of combined condensate and residue drawn off from tray 28 might be about 570° F. and the light gas oil drawn from tray 27 might have a temperature of about 475° F. Under these conditions the combined condensate and residue drawn from tray 28 might have a gravity approximating 22° A. P. I. 10

The viscosity breaking heater may be operated 20 under such conditions that the oil emerges therefrom at a temperature of, for example, 860° F. and a pressure of 200 pounds per square inch, while the vapor phase heater may be so controlled as to discharge the oil therefrom at a temperature of, for example, 960° F. and a pressure of 200 pounds per square inch. The soaking drum 7, evaporator tower 2 and fractionator tower 3, may be operated under substantially the same 25 pressure, the only difference in pressure being 30 that necessary to cause a flow of the products through these chambers and their pipe lines. However, if desirable the vapor phase cracking operation may be carried out at a lower or even somewhat higher pressure, but 200 pounds will 35 generally be found to be preferable where the temperature mentioned is maintained. The viscosity breaker need not operate under the same 40 pressure as that of the vapor phase heater, higher or lower pressure may be used to secure best results with different charging stocks. The pressure desired can be maintained by proper manipulation of the pressure reducing valve 60. Light naphtha flash drum 11 and secondary flash 45 drum 18 are preferably maintained at substantially atmospheric pressure, whereby the desired products are readily separated in vapor form, but somewhat higher pressures might be maintained 50 with a corresponding lesser amount of vaporization. The amount of cracking per pass attained in the viscosity breaker and vapor phase heater may be varied to suit the characters of different 55 charging stocks, however, with a charging stock such as that mentioned hereinbefore the specific temperatures and pressure already mentioned are suitable.

The cracking per pass of the vapor phase heater, in terms of end point gasoline, may be 13 to 15%, while the total cracking per pass, including that attained in the soaking drum 7, might be 18 to 19%. The viscosity breaker on the other hand is advantageously operated to produce only a moderate amount of cracking such as to convert from 8 to 10% of the stock charged thereto into gasoline and into a product suitable as vapor 60 phase charging stock.

I have found that if, when employing vapor phase soaking drum 7, there is a tendency for coke to deposit in the vapor line 1a leading to the 65 evaporator tower 2, such deposition may be obviated by flushing the line continuously with a suitable fluxing oil and I have further found that the crude residuum from the bottom of flash drum 18 is particularly adapted for this purpose. 70 75

The requirements are that the oil be non-volatile at the temperature and under the conditions prevailing in the vapor line 1a and at the same time be indisposed to form coke. Particles of incipient coke carried by the vapors are fluxed by this oil and prevented from aggregating as solid coke masses on the walls of the passage. The heavy residuum withdrawn by line 70 and valve 71 is preferably diluted in accumulator 73 with gas oil 10 withdrawn from tower 3 by lines 53 and 72, and partially cooled in cooler 72a. The flushing oil is then forced by pump 74 and line 75 thru cooler 76 to the vapor line 1a where it may be introduced at one point as shown or at a plurality of points 15 along the line.

While I have described a particular embodiment of my invention for the purposes of illustration it should be understood that various modifications and adaptations thereof may be made 20 within the spirit of the invention as set forth in the appended claims.

I claim:

1. The process of treating hydrocarbon oils which comprises introducing hot lightly cracked 25 heavy oil into a first vapor separating zone wherein vapors are separated from said oil, introducing a hot cracked tar into a second vapor separating zone wherein vapors are separated, combining, in a third zone, vapors, produced in said 30 vapor separating zones and forming a reflux condensate therefrom, removing uncondensed vapors from said third zone and condensing them, introducing said reflux condensate into a fourth zone, separately introducing hot vapor phase 35 cracked products into said fourth zone in counter-current contact with said condensate whereby a portion of said condensate is vaporized, removing uncondensed vapors from said fourth zone and forming a final desired product therefrom, and 40 removing liquid residual constituents of said vapor phase cracked products from said fourth zone and utilizing them as a source of said hot cracked tar first mentioned.

2. A process in accordance with claim 1 where- 45 in said first and second vapor separating zones are maintained under substantially atmospheric pressure and said fourth zone is maintained under a pressure in the order of 200 pounds per square inch.

3. A process in accordance with claim 1 where- 50 in the uncondensed vapors in the fourth zone are subjected to fractionation to form an uncondensed vapor of the desired end point and reflux condensate, said uncondensed vapor being with- 55 drawn to form a final desired product while said reflux condensate is cracked in the vapor phase to form said vapor phase cracked products.

4. A process in accordance with claim 1 where- 60 in said tar is withdrawn from said fourth zone.

5. A process in accordance with claim 1 where- 65 in charging stock for the system is contacted with the combined vapors from the first and second vapor separating zones and introduced with said condensate into said fourth zone.

6. The process of treating hydrocarbon oil which comprises introducing relatively heavy charging oil into a vapor separating zone wherein 70 said oil is partially vaporized by contact with hot oil vapors, leaving unvaporized liquid oil, intro- 75 ducing said liquid oil into an intermediate point in a second zone containing hot vapors, to be heated by countercurrent contact with said vapors, removing heated liquid oil from an intermediate point in said second zone, lower than 80 said point first mentioned, cracking the removed 85

liquid oil, separating resulting cracked products into vapors and a residue, withdrawing said residue from the system, introducing said vapors into said vapor separating zone first mentioned, removing vapors from said second zone, partially condensing the removed vapors in a fractionating zone, leaving uncondensed light vapors, and a reflux condensate, forming a final desired product from said light vapors, separately cracking said reflux condensate in the vapor phase, introducing 10 resulting cracked products into a low point in said second zone, and separately withdrawing unvaporized residue from the bottom of said second zone.

7. The process of treating hydrocarbon oil 15 which comprises introducing relatively heavy hydrocarbon oil into a vapor separating zone, separately introducing hot vapors into said zone in counter-current contact with said heavy oil, removing from said zone as a mixture unvapor- 20 ized portions of said heavy oil and condensed portions of said vapors, heating the removed mixture to a moderate cracking temperature, separating light vaporous fractions from the resulting lightly cracked products, in a second zone, leaving liquid 25 residue, withdrawing said liquid residue from the process, fractionating said light vaporous fractions in a third zone, out of contact with the vapors liberated in said vapor separating zone, to form a heavy condensate, condensing resulting 30 fractionated vapors as a desired product, introducing said heavy condensate into said vapor separating zone as said heavy oil first-mentioned, and removing uncondensed vapors from the top 35 of the first-mentioned vapor separating zone and forming a desired product therefrom.

8. A process in accordance with claim 7 where- 40 in heavy charging oil is contacted with the light vaporous fractions separated from said lightly cracked heavy oil in said third zone, and unvaporized portions of said charging stock are introduced into said vapor separating zone first-mentioned mixed with said heavy condensate.

9. The process of treating hydrocarbon oil 45 which comprises separating from crude oil by aid of heat derived from cracked vapors, without cracking, light gas oil and topped crude, introducing the resulting topped crude directly into an intermediate point in a vapor separating zone containing hot vapors, to be heated by contact 50 with said vapors, causing said topped crude and hot vapors to flow countercurrent to one another in said separating zone, removing resulting vapors from a high point in said separating zone and fractionating them out of contact with vapors from said crude oil, to form a final desired light distillate and a reflux condensate, removing the heated topped crude from an intermediate point in said separating zone lower than said 55 point first-mentioned, cracking the removed topped crude, separating the resulting cracked products, in a second vapor separating zone, into vapors and liquid residue, preventing passage of said vapors last mentioned into said vapor separating zone first mentioned, withdrawing said residue from the process and utilizing vapors so obtained as a source of said hot vapors first 60 mentioned.

10. A process in accordance with claim 9 70 wherein said reflux condensate from said fractionating step is cracked separately from said topped crude, the resulting hot cracked products are introduced into said separating zone first mentioned at a point below said intermediate 75

point and liquid residue is withdrawn from the base thereof.

11. The process of treating hydrocarbon oil which comprises introducing heavy oil containing lighter vaporizable constituents into a stripping zone in countercurrent contact with highly heated vapors from a first source and a second source, whereby said heavy oil is partially vaporized, removing resulting residual oil from said 5 stripping zone and passing it into a second zone in countercurrent contact with highly heated cracked vapors whereby additional vaporization of said residual oil and partial condensation of said cracked vapors occurs, removing a mixture 10 of unvaporized residue and condensate from said second zone and passing it through a first cracking zone wherein it is raised to a cracking temperature and subjected to conversion, introducing the resulting cracked products into a third zone 15 wherein vapors separate from liquid residue, withdrawing resulting residue from the process, utilizing resulting vapors as said vapors from said first source, fractionating vapors from said second zone in a fourth fractionating zone to 20 form a final desired distillate and a reflux condensate, passing reflux condensate so obtained through a second cracking zone wherein it is raised to a cracking temperature and subjected to conversion, separating resulting cracked products 25 into vapors and a liquid residue, utilizing 30

said vapors as said highly heated cracked vapors in said second zone, and passing said liquid residue last mentioned into a flashing zone under reduced pressure, utilizing the flashed vapors as said vapors from said second source and separately withdrawing the flashed residue from the process.

12. The process of treating hydrocarbon oil which comprises stripping crude charging stock of lighter products by contact with hot vapors in a stripping zone, forming reduced crude, introducing resulting reduced crude into a dephlegmating zone in contact with hot vapors, removing liquid oil comprising unvaporized constituents of said reduced crude from said dephlegmating zone, cracking the removed liquid oil, separating the resulting cracked product into vapors and residue, isolating said residue from the process, directing vapors thus separated into said stripping zone, separately cracking a clean condensate stock, introducing resulting hot cracked products into a separating zone wherein separation of vapors from residue takes place, passing separated vapors from the separating zone to aforesaid dephlegmating zone, withdrawing residue from said separating zone, removing vapors from said dephlegmating zone and forming a desired product therefrom.

HAROLD R. SNOW. 30
